UNITED STATES PATENT OFFICE.

THOMAS BEAGHEN, JR., OF MOUNT VERNON, NEW YORK.

TANK CAR.

Application filed September 21, 1921. Serial No. 502,168.

This invention relates to tank cars, and it has special reference to tank cars in which the tanks are carried at their ends upon suitable supports and are anchored to the car underframe intermediate the end supports.

Tank cars of this general construction have been employed heretofore in the art, but the anchorage connections have been rigid in construction and have served not only to prevent bodily longitudinal movement of the tank but also to assist in its support. With this construction, undesirable and excessive strains and stresses have been imposed upon the tanks and upon the rivets by means of which the anchorage devices have been secured thereto, and therefore, injury to the tanks and rivets is likely, accompanied by consequent leakage of the tank contents. These strains and stresses result either from inaccurate alignment of the end supports with the center anchorage, or from the wear of the end-supporting blocks under conditions of use, thereby permitting the tank to settle, and imposing undue weight upon the center anchorage.

Accordingly, one of the objects of the present invention is to provide a tank car of the above-indicated character, which shall embody, intermediate the end supports, a tank anchorage which is so constructed and arranged as to prevent bodily longitudinal shifting movements of the tank and at the same time be capable of yielding vertically to a certain extent, so that the weight of the tank is always carried by the end supports and the tank is adapted to accommodate itself to any irregularities in the alignment of the end supports or to the wear of the supporting end blocks. The tank anchorage of the present invention, therefore, is not intended to support the tank but merely to tie the tank rigidly to the underframe and to yield vertically to a sufficient extent to eliminate any undesirable strains and stresses which might shear the attaching rivets and rupture the tank. These anchorage devices are fastened and shaped in such manner as to embody pronounced loops or bends, probably having reversed curved undulations in the respective legs thereof which serve to lend a certain amount of yielding or resilience in a vertical direction for the above-indicated purposes.

Another object of the invention is to provide a structure of the above-mentioned type which is provided with a discharge outlet

pipe or pipes projecting laterally from beneath the tank and embodying a valve or valves and suitable operating mechanisms therefor that are located at the side of the car where they are conveniently accessible to be handled. Accordingly, the anchorage devices preferably comprise two sets of tie members such as already described, which are slightly spaced apart in a longitudinal direction to permit the discharge outlet pipes, valves and operating mechanisms to be conveniently located in the space between them.

The invention will best be understood from the following description of the accompanying drawings, which illustrate a preferred embodiment of the invention and in which:

Fig. 1 is a view in side elevation of a tank car constructed in accordance with the present invention.

Fig. 2 is an enlarged detail view of a portion of the structure shown in Fig. 1, illustrating particularly the construction and location of the anchorage devices and the controllable discharge outlet pipes.

Fig. 3 is a sectional view along the section line 3—3 of Fig. 2.

Fig. 4 is a sectional view along the section line 4—4 of Fig. 1.

Referring to the drawings, the structure illustrated comprises, in general, a plurality of trucks 10 upon which an underframe 11 is mounted, the underframe being provided with end supporting saddles 12 having wear blocks 13 secured thereto for supporting an elongated tank 14 at its respective ends. The weight of the tank is carried substantially entirely by the wear blocks and end saddles, and the tank is rigidly tied to the underframe to anchor it against bodily longitudinal movements by means of anchorage devices 15, which are rigidly secured to the tank and to the underframe, and which are slightly spaced apart to provide room for a plurality of laterally projecting discharge outlet pipes 16, a valve 17 and a laterally projecting operating mechanism 18.

The trucks 10 may be of any suitable and well-known construction and are adapted to carry or support the underframe 11 in accordance with customary practice. The underframe 11 may constitute a single longitudinally extending center sill, as illustrated in the drawings, or, if desired, a plurality of longitudinal sills may be employed. The center sill illustrated comprises a plu-

rality of longitudinally extending and vertically disposed channel members 20 to which are secured horizontal plates 21 and 22 to form a substantial unitary box-like structure. Near each end of the sill is a supporting structure 23 projecting laterally in opposite directions therefrom, and the respective arms of each of these structures are provided with V-shaped members 24, each pair of which constitutes an end saddle 12. The V-shaped members 24 of each set of end saddles are inclined inwardly toward the center line of the car underframe and are provided with a plurality of longitudinally disposed wear blocks 13, which are suitably secured thereto, the space between the respective members 24 of each set being also filled with wear blocks 13. These wear blocks are preferably of wood or other suitable material and the upper surfaces thereof are shaped to conform to the configuration of the tank 14 so that the tank may rest firmly therein. A plurality of straps 25 are employed for surrounding the tank and tying it in position against displacement. With this construction, the tank 14 merely rests upon the wear blocks 13 of the end saddles 12 and is supported thereby at two points adjacent the respective ends of the tank.

In order to restrain the tank against bodily longitudinal movements while at the same time permitting the tank to expand and contract in a longitudinal direction, as may be occasioned by variable temperature conditions, the tank is anchored to the underframe at a point intermediate the end saddles by means of the anchorage devices 15. Preferably these devices comprise two sets of oppositely disposed tie members or plates which are formed in the manner shown in Fig. 3, the two sets being slightly spaced apart for the purposes already mentioned. The anchorage members of each set are placed on opposite sides of the tank center line and are in the preferred embodiment of the invention, located substantially midway between the ends of the tank, but their location is not so restricted and, in fact, additional sets of anchorage devices may be employed, as indicated, for instance, in dotted lines in Fig. 1, to which the reference numeral 15^a is applied. The tie members 15 may conveniently be made of metal plates which are bent into such form as to provide pronounced bends 27, or they may be cast, forged or otherwise constructed, so long as they are yielding or resilient in a vertical direction. These plates are rigidly and tightly secured by means of rivets 28 to the tank 14 and also to the projecting flanges 29 of the center sill 11 by means of rivets 30.

The function of the bends 27, as already stated, is to permit of a certain degree of vertical yielding in order to avoid imposing upon the tank or the attaching rivets undue

stress or strain which might result in shearing the rivets and rupturing the tank with the consequent leakage of the tank contents. This resilient or yielding element in the anchorage devices is of especial importance as it permits the tank to accommodate itself to irregularities in the alignment of the end saddles and supporting wear blocks which may result either from inaccurate assembling or from wear of the blocks under conditions of use. This character of anchorage, therefore, permits of some latitude in the positioning of the saddles and wear blocks during assembling, and furthermore, allows the tank to settle to quite an appreciable extent due to the wear of the supporting blocks without imposing injurious strain upon the tank or the attaching rivets. Furthermore, slight transverse shifting or rocking movements of the tank are permitted without detrimental effect. The anchorage devices 15, however, are substantially rigid in a longitudinal direction and prevent bodily movement of the tank. Absolute rigidity is not necessary, or in fact desirable, as there may be slight elongations or contractions of the tank between the two sets of anchorage devices due to temperature changes. Such variations, of course, are extremely slight, on account of the short length of the space and are, therefore, almost inappreciable. However, the configuration of the anchorages or tie members is such that these slight changes may be accommodated without the development of undue strains, and injury that may result therefrom.

The respective legs of each of the pronounced loops or bends of the anchor plates are preferably provided with reverse curved undulations as clearly illustrated in Figure 3 of the drawings. The object of these undulations is to lend increased resiliency or capability of bending to the anchor plates, whereby undesirable stresses in the plates under operating conditions are effectively eliminated.

For the purpose of withdrawing the contents of the tank, the tank is provided with a plurality of outlet discharge pipes 16 which project laterally in opposite directions from the valve 17, which is attached to the bottom of the tank and communicates therewith. These discharge pipes 16 and valve 17 are located intermediate the two spaced sets of anchorage devices 15. The valve 17 is provided with an operating handle or mechanism 18 which also projects laterally through the space between the anchorage devices and into position where it is readily accessible to the operator. It is preferable to provide the respective discharge pipes 16 with individual control valves 17^a.

Obviously the structural details shown and described may be modified greatly while still retaining the advantages and benefits

of the invention. The scope of the invention, therefore, should not be restricted in any sense to the particular illustrative embodiment set forth, but is defined in the appended 5 claim.

Having set forth the nature and described a preferred embodiment of the invention, what is claimed as new is:

10 In a tank car, the combination with a supporting frame, tank supports mounted at the ends thereof and a tank resting upon and carried by said supports, of a plurality of closely adjacent anchorage devices disposed interme-

15 diate the tank supports and rigidly secured to said tank and said underframe for preventing bodily longitudinal movements of said tank, a plurality of discharge outlet pipes communicating with said tank and projecting laterally through the space between said anchorage devices, a valve for controlling 20 said outlet pipes and operating means for said valve projecting laterally through the space between said anchorage devices.

In witness whereof, I have hereunto set my hand this 17th day of September, 1921.

THOMAS BEAGHEN, JR.
